(57) **CLAIM**

The ornamental design for a toy, as shown and described.

DESCRIPTION

FIG. 1 is a perspective view of an embodiment of a toy;
FIG. 2 is another perspective view of the toy shown on the
wrist of a user;

FIG. 3 is a rear elevational view of the toy;

FIG. 4 is front elevational view of the toy;

FIG. 5 is a left side elevational view of the toy;

FIG. 6 is a right side elevational view of the toy;

FIG. 7 is a top plan view of the toy; and,

FIG. 8 is a bottom plan view of the toy.

The broken lines shown in FIGS. 1-8 are included for the
purpose of illustrating environmental elements only and form
no part of the claimed design.
